UNITED STATES PATENT OFFICE.

BENJAMIN SHAW SMITH, OF MEXIA, TEXAS.

ADDING-MACHINE-RIBBON ATTACHMENT.

Application filed April 8, 1924. Serial No. 704,919.

The present invention consists of a ribbon spool attachment for adding machines and like structures which employ ribbons used for expressing indicia which urges the ribbon against paper or the like trained around a platen.

An object of the invention is to provide an attachment for adding machine ribbon spools which permits a new ribbon to be substituted for an old one in a facile and expeditious manner without the assistance of a "service man".

It is well known in the art to equip a ribbon spool with an inelastic element to which one end of a ribbon may be engaged, but it is the principal object of the present invention to use an elastic medium on the ribbon spool which medium may be expanded into a position where it is readily accessible in the back or some other part of the machine so that a new ribbon can be pinned thereto. In this way, the necessity of removing parts of the machine in order to apply a new ribbon is reduced to a minimum.

Other objects of the invention will be apparent from the following description of the present preferred form of the invention taken in connection with the accompanying drawings wherein:

Fig. 1 is a plan view of the elastic means constructed in accordance with the present invention;

Fig. 2 is a side elevational view thereof;

Fig. 3 is a side elevational view of the invention illustrating the application of the same in an adding machine, the latter being shown in fragmentary section;

Fig. 4 is a detail enlarged fragmentary plan view of the present invention; and

Fig. 5 is a detail enlarged fragmentary elevational view illustrating application of the invention to a ribbon spool.

In the drawings, in order to illustrate the application of the present invention a portion of an adding machine generally designated 6 is provided which may be of standard construction and includes a lower ribbon spool 7 and an upper ribbon spool 8. The adding machine likewise includes a casing having a removable upper part 9 and a movable plate 10 in which an opening 11 is formed to permit engagement of type bars 12 therethrough for urging a ribbon 13 into impingement with paper or the like which may be trained about a platen 14. The platen 14 is movable, in a manner well known in the

art, and has a portion thereof which normally projects into the opening 11 of the plate 10. The device of the present invention consists of an elastic body 15 which may be made of rubber or like material and may be of oblong configuration as shown in the drawings. The opposite ends of the elastic means or body 15 is grooved or rabbeted to accommodate inelastic tabs 16. It is, of course, to be understood that the tabs 16 may be otherwise connected to the elastic body 15 but the manner of connection herein shown serves to illustrate the principle of the invention.

In use of this device one of the tabs 16 is adapted to be engaged with the lower ribbon spools 7 and to be clamped from displacement thereon by a clamping clip 17 of standard construction. The opposite tab 16 is adapted to be pinned or otherwise secured to the ribbon 13, as indicated at 18. Consequently, when a new ribbon is to be substituted for the old one the platen 14 is moved clear of the opening 11 thereby permitting the fingers of the operator to be inserted through the opening 11 and grasp the ribbon 13. Pressure is exerted upon the ribbon 13 until the elastic element 15 is flexed to a point where the tab 16 which engages the ribbon 13 is in proximity to the opening 11. When in this position the old ribbon can be disengaged from the tab 16 and withdrawn from the upper spool in an obvious manner. One end of the new ribbon is then pinned or otherwise secured to the outer of the tabs 16 and pressure released from said tab so as to permit the elastic element 15 to contract and draw the ribbon downwardly toward the spool 7. The upper roller 8 is removed by disengaging the upper part 9 of the adding machine casing and the opposite end of the new ribbon rolled thereon. In view of the above it is apparent that in order to attach a new ribbon it is unnecessary to remove the lower spool 7 and hence considerable time and labor is saved in disengaging parts of the adding machine so that access can be gained to the lower roller.

Different changes may be made in the device especially in the materials employed, size and shape of the device, etc. within the scope of the claims hereto appended.

What is claimed is:

1. In combination with an adding machine casing provided with a platen receiving

- opening therein and equipped in said casing with ribbon spools one of which is arranged above and the other below the opening, an attachment for connection to an inking ribbon including an element one end of which is in connection to one of the ribbon spools, said element being elastic to permit the same to be flexed for urging its opposite end into proximity to the platen opening.
- 5 10 2. In combination with an adding machine casing provided with a platen receiving opening therein and equipped in said casing

with ribbon rollers arranged above and below the opening, an inelastic tab secured to one of said ribbon rollers, an elastic element 15 one end of which is engaged with said tab and equipped with a ribbon engaging inelastic tab, said elastic element being flexible to permit the ribbon engaging tab to be urged into proximity to the platen opening 20 of the casing.

In testimony whereof I affix my signature.

BENJAMIN SHAW SMITH.
